UNITED STATES PATENT OFFICE.

ALICE H. KNAPP, OF ASBURY PARK, NEW JERSEY.

NURSING-GARMENT.

1,098,155.

Specification of Letters Patent. Patented May 26, 1914.

Application filed March 7, 1913. Serial No. 752,782.

To all whom it may concern:

Be it known that I, ALICE H. KNAPP, a citizen of the United States, residing at Asbury Park, in the county of Monmouth, State of New Jersey, have invented certain new and useful Improvements in Nursing-Garments; and I do hereby declare the following to be a full, clear, and exact description of the invention, such as will enable others skilled in art to which it appertains to make and use the same.

The present invention relates to wearing apparel and has particular application to certain novel and useful improvements in a waist or similar upper garment adapted to be worn by nursing mothers.

In carrying out my invention it is my purpose to provide a nursing garment which is so designed and constructed that when it is desired to nurse the infant the latter may be placed at the breast without the inconvenience, embarrassment and exposure usually incident to the wearing of the ordinary form of waist or like upper garment.

A further object of my invention is the provision of a special type of nursing garment wherein the necessity of partly undressing, as is required when an ordinary waist opening in the back or center front is worn, is entirely eliminated. Furthermore, the rapid destruction of the mother's ordinary garments due to constant soiling while the child is nursing is entirely avoided and the consequent expense incident to replacing such ruined clothing is obviated.

Still a further object is to provide a garment which when not in use is so disposed and secured as to have the appearance of an ordinary waist, so that its functions will not be evident to ordinary observation, while when it is desired to proceed with the nursing the garment may be quickly arranged for such purpose.

With the above recited objects and others of a similar nature in view, my invention consists in the construction, combination and arrangement of parts set forth in and falling within the scope of the appended claim.

In the accompanying drawings: Figure 1 is a perspective view of a preferred type of my nursing garment and showing one of the

trimming bands or plaits turned back with 55 the closure flap for one of the breast openings of the garment opened to substantially the position of actual use, the opposite breast opening and flap of the garment being closed by the overlying trimming band 60 or plait. Fig. 2 is a front view of a portion of the waist shown in Fig. 1 with the covering or concealing plait removed, in this case the flap being formed integral with the material of the waist portion, and is shown 65 in buttoned position. Fig. 3 is a view of the inner face or back portion of the waist section shown in Fig. 2. Fig. 4 is a front view of a section of a modified style of garment, in this case the closure flap for the breast 70 opening constituting a separate piece which is attached to one piece of the waist at the structural seam thereof. Fig. 5 is a view of the inner face of the waist section shown in Fig. 4 and showing the separate sections 75 stitched at the structural seam of the waist section. Fig. 6 is a front view of a waist section showing another style of modified form, in this form the flap constituting a 80 separate piece stitched to a vertical seam adjacent the breast opening. Fig. 7 is a view of the opposite or inner face of the garment section shown in Fig. 6. Fig. 8 is a horizontal sectional view taken on the line 8—8 of Fig. 2. Fig. 9 is a similar sectional view 85 taken on the line 9—9 of Fig. 4. Fig. 10 is a horizontal sectional view taken on the line 10—10 of Fig. 6.

In the present instance I have shown my invention as embodied in the form of an outside waist, although I wish it to be understood that it is not limited in its particular application to this specific type of garment, as it may be employed advantageously in connection with corset covers, under vests, 95 union suits, night gowns, dressing saques, wrappers, kimonas, and waists of any material or style of manufacture.

This invention embraces among its novel features, an upper garment, such as a waist, 100 having a pair of peculiarly constructed elongated openings in the front thereof which, when the waist is being worn, are designed to lie disposed over the breast in a manner to permit ready and convenient access for 105

the purpose of nursing, these openings being adapted to be closed by means of flap members which may be formed integral with the material of the waist, or may be in the 5 nature of separate pieces stitched or otherwise fastened to the body of the waist alongside the openings. I have herein shown and described three novel and distinct arrangements of the flap, for it will be seen that in 10 the styles shown in Figs. 1 to 3 of the drawings the peculiarly constructed flap is cut from the same piece of material as the adjacent waist section, while in Fig. 4 the flap is a separate piece attached to the structural seam of the garment which extends 15 from the lower edge of the waist to the shoulder and in Fig. 6 I show the separate flap attached to a short seam, while the structural seam from the shoulder to the 20 bottom edge of the waist is omitted.

Referring now to the accompanying drawings in detail and particularly to Figs. 1 to 3 inclusive, the letter A designates a nursing garment embodying my invention. In 25 the front of the waist and directly over each breast I form an opening 1 by cutting the material of the waist on the vertical line 2 and the horizontal lines 3—3. By so cutting the opening I form an elongated recess over the breast 30 which, when the covering flap, hereinafter described, is pushed to one side will permit the material forming the sides of the opening to be separated or drawn apart to a greater extent than were the sides of such opening formed closer together as by the 35 mere act of vertically slitting the material. In Figs. 1 to 3 I provide a closure for the opening which is in the nature of a flap 4 formed integral with the material of the 40 waist, at one of the longitudinal sides of the opening, this flap being of suitable size and of proper shape to overlap and close the opening, and is preferably formed of a double thickness of material united by a 45 line of stitching 5. This flap is further provided with a vertically arranged row of buttons 6 spaced a suitable distance apart adapted to be passed through corresponding button holes 7 formed in the material of 50 the waist adjacent the opposite longitudinal edge of the opening 1. It will of course, be understood that other means for fastening the flap in its closed position may be employed in lieu of buttons and buttonholes, 55 but the lateral manner is preferable, for the reason that the buttons are easily manipulated and do not require undesirable pressure against the breasts, as is the case with snap fasteners and other forms of fastening 60 means.

If desired, each breast opening when closed by a flap may be covered by a band of trimming or a plait 8 adapted to extend vertically from the shoulder to a point adjacent 65 the waist of the person, and this plait as is

shown in Fig. 1 may be stitched as at 9 at the shoulder portion of the garment, while the breast section and lower portion of the plait illustrated at 10 is free or unattached so that it may be thrown back or to one side 70 to expose the breast opening when the infant is to be nursed. In nursing, this plait or trimming material may be draped in such manner as to provide further concealment. When both the plaits or trimming bands 75 overlie the openings and their flaps, the latter are completely concealed, and as the lower ends of the plaits may be fastened into the garment adjacent the waist, as by means of the buttons 11, the garment will have the 80 appearance of an ordinary outer waist. In Figs. 4 and 5 the closure flap for each breast opening 1, is shown at 12, and is in the nature of a separate piece stitched to one longitudinal side of the opening along the 85 structural seam 13 of the waist which seam runs vertically of the garment.

In Figs. 6 and 7 the flap for each opening 1 is in the nature of a separate piece shown 90 at 14, which is attached at one longitudinal side of the opening by means of the short seam or line of stitching shown at 15. The utility and value of the flap is the same in all the styles shown, whether it be cut as a 95 part of the garment, or as a separate piece attached by means of the structural seam, or a separate piece attached to the backward edge of a short seam which does not run beyond the ends of the flap which is placed underneath.

If desired, an appearance of extra fullness over the bust may be given by making a tuck of suitable width, for instance an inch at each side near the arm scye and shown at 16, this being stitched down for a few inches 105 and its fullness released directly opposite the opening.

It will be seen that I have provided a novel, convenient and neat appearing garment for the purposes hereinbefore mentioned, and which may be readily adapted for use when it is desired to nurse, while at other times it may be arranged to have the appearance of an ordinary waist.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claim.

What is claimed is:

A nursing garment having a pair of vertical openings formed therein adapted to overlie the breasts of the wearer, and a closure flap for each opening connected at its outer vertical longitudinal edge portion to the material of the garment adjacent the 130

outer longitudinal edge of the opening, said flap being folded inward across the opening to close the latter when not in use, means for fastening the flap in its closed position, and 5 a strip of material fastened to the upper portion of the garment and adapted to overlie the flap and opening, said material adapted to be detachably fastened to the

garment at a point adjacent its lower end portion. 10

In testimony whereof, I affix my signature, in the presence of two witnesses.

ALICE H. KNAPP.
